UNITED STATES PATENT OFFICE.

CURTIS HUSSEY VEEDER, OF HARTFORD, CONNECTICUT, ASSIGNOR TO THE VEEDER MANUFACTURING COMPANY, OF HARTFORD, CONNECTICUT, A CORPORATION OF CONNECTICUT.

COUNTING MACHINE.

Application filed January 6, 1926. Serial No. 79,518.

In Letters Patent of the United States No. 1,321,181, dated December 30, 1921, and No. 1,537,512, dated May 12, 1925, there are shown and described duplex counting machines, having two counting mechanisms, either one of which can be put into operative relation with the moving part of the machine, the number of operations of which are to be registered, so that the number of 10 operations during a given period of time can be registered independently of the number of operations during another period of time. Such duplex counting machines are widely employed in manufacturing plants, 15 such as weaving mills, which are operated on a two-shift basis, that is with two-shifts of operatives within the space of twenty-four hours. Some mills run on a three-shift basis and the present invention has for 20 its primary object to provide a satisfactory three-shift counting machine, with three separate counting mechanisms, each adapted to register the number of picks of a loom, for example, in the period of one shift, pro- 25 vision being made whereby each of the counting mechanisms can be operatively connected at will with the moving part of the machine of which the operations are to be registered, while the other counting 30 mechanisms are held from movement. While the construction to be described has been developed with particular reference to its use for three shifts, it will be apparent that the improved construction is adaptable 35 for use with two counting mechanisms as well as for three or more. The invention is concerned mainly with the mechanical devices by which each counting mechanism is placed in operative relation with the moving part and with mechanical devices by 40 which the counting mechanisms not coupled to the moving part are held from operation.

The invention will be more fully explained hereinafter with reference to the 45 accompanying drawings in which it is illustrated and in which:

Figure 1 is a view in front elevation of a counting machine equipped with the present improvements, portions of the front plate 50 being broken out to show parts otherwise concealed.

Figure 2 is a view in horizontal section on the plane indicated by the broken lines 2-2 of Figure 1.

Figure 3 is a view in vertical section on 55 the plane indicated by the broken line 3-3 of Figure 1.

Figure 4 is a detail view, partly in elevation and partly in vertical section showing 60 particularly the locating devices.

Figures 5, 6 and 7 are detail views illustrating particularly the braking devices.

In the embodiment of the invention illustrated in the drawings, there is provided a suitable casing *a* having a front plate *a'* 65 formed with sight openings *a*² through which the three sets of number wheels *b* may be read. The numbering mechanisms may be constructed and arranged to operate in any usual or suitable manner, each being 70 shown as provided with a gear *d*, which in this instance is conveniently formed as an internally toothed gear. Each of the gears *d* is adapted to be engaged at will by a common driving pinion *e* which is carried by a 75 shifting arm *f* adapted to be moved in an axial direction and to be swung upon its axis to place the pinion *e* in engagement with one or another of the gears *d*.

The arm *f* is fixed on a shaft *g* which is 80 mounted to oscillate and to have axial movement in bearings *a*³ carried by the casing *a*. The shifting shaft *g* carries at one end an operating handle *g'* and is held normally in engaging position by a spring *g*² which 85 bears at one end against a shaft bearing *a*⁴ and at the other end against a hub *h* which is fixed on the shaft and carries a locating or positioning arm *h'*. The latter has at 90 its end a pin *h*² adapted to enter one or another of holes *h*³ in a segment *h*⁴ which is secured to the inside of the casing.

Also mounted in bearings *a*⁵ of the casing 95 is the main driving shaft *i* which is adapted as at *i'* to be coupled to the moving part of the machine, the operations of which are to be registered. This shaft, in the arrangement shown, carries a worm *i*² which engages a gear *i*³ on a vertical shaft *i*⁴. The latter carries a worm *i*⁵ which engages a 100 gear *k* coaxial with the shifting shaft *g*. The gear *k* is carried by a sleeve *k'* which is mounted loosely on the shifting shaft *g* and may be held from axial displacement by a sleeve *a*⁶ which is mounted in a bracket 105 *a*⁷ of the casing. At the other end of the sleeve *k'* is a wide faced gear *k*² which meshes with an idler *k*³ mounted on the arm

f. The idler in turn meshes with a gear h^4 which carries the driving pinion e above mentioned.

It will now be seen that by axial movement of the shifting shaft g against the pressure of the spring g^2 the pinion e can be withdrawn from engagement with one of the internally toothed gears d and can then be moved about the axis of the shaft g , by means of the handle g' , into position for engagement with another one of the gears d , in which engagement it will be held by the spring g^2 .

It is desirable that the counting mechanisms b , which are not at the time operatively connected with the driving shaft, be held against accidental movement. For this purpose, there is associated with each counting mechanism a shaft l , which bears at one end a brake arm l^4 held normally in contact with the periphery of the internally toothed gear d by a coiled spring l^5 applied to the shaft. At its other end each shaft l carries an arm l^1 , l^2 or l^3 , as the case may be, arranged to coact with a wide cam h^5 formed on the hub h of the locating arm h' . As the locating arm is swung with the shaft g and the handle g' to place the pinion e in engagement with one or another of the internally toothed gears d , the toe of the cam h^5 coacts with the corresponding arm l^1 , l^2 or l^3 of the brake shaft l of the counting mechanism to move the brake arm l^4 from contact with the periphery of the internal gear d , the brake arms of the other two counting mechanisms being at the same time held in contact with the corresponding gears d by their respective springs l^5 .

It will be understood that various changes in details of construction and arrangement can be made to suit different conditions of use and that, except as pointed out in the claims, the invention is not restricted to the particular construction shown and described herein.

I claim as my invention:

1. The combination with a plurality of devices to be actuated each having a driving gear, the axes of said driving gear being parallel, and a driving pinion movable axially and in an arc concentric with its axis into and out of driving engagement with each of the driving gears, and means for actuating the driving pinion.

2. The combination with a plurality of devices to be actuated each having an internally toothed driving gear, the axes of said driving gears being parallel, and a driving pinion movable axially and in a plane radial to its axis into and out of driving engagement with each of the driving gears, and means for actuating the driving pinion.

3. The combination with a plurality of devices to be actuated each having a driving gear, the axes of said driving gears being

parallel and in the same plane and a driving pinion movable axially and in an arc concentric with its axis into and out of driving engagement with each of the driving gears, and means for actuating the driving pinion.

4. The combination with a plurality of devices to be actuated each having an internally toothed driving gear, the axes of said driving gears being parallel and a driving pinion movable axially and in an arc concentric with its axes into and out of driving engagement with each of the driving gears, and means for actuating the driving pinion.

5. The combination with a plurality of devices to be actuated each having an internally toothed driving gear, the axes of said driving gears being parallel and in the same plane and a driving pinion movable axially and in an arc concentric with its axis into and out of driving engagement with each of the driving gears, and means for actuating the driving pinion.

6. The combination with a plurality of devices to be actuated each provided with a driving gear the axes of the driving gears being parallel, of means for actuating any one of said driving gears at will from a common shaft comprising a shifting arm adapted to be swung about an axis and also movable in an axial direction, a driving pinion carried by the shifting arm and means for actuating the driving pinion from the common shaft.

7. The combination with a plurality of devices to be actuated each provided with a driving gear the axes of the driving gears being parallel and in the same plane, of means for actuating any one of said driving gears at will from a common shaft comprising a shifting arm adapted to be swung about an axis and also movable in an axial direction, a driving pinion carried by the shifting arm and means for actuating the driving pinion from the common shaft.

8. The combination with a plurality of devices to be actuated each provided with an internally toothed driving gear the axes of the driving gears being parallel, of means for actuating any one of said driving gears at will from a common shaft comprising a shifting arm adapted to be swung about an axis and also movable in an axial direction, a driving pinion carried by the shifting arm and means for actuating the driving pinion from the common shaft.

9. The combination with a plurality of devices to be actuated each provided with an internally toothed driving gear the axes of the driving gears being parallel and in the same plane, of means for actuating any one of said driving gears at will from a common shaft comprising a shifting arm adapted to be swung about an axis and also movable in an axial direction a driving pinion carried by the shifting arm and means for actuati-

ing the driving pinion from the common shaft.

10. The combination with a plurality of devices to be actuated each provided with a driving gear the axes of the driving gears being parallel, of means for actuating any one of said driving gears at will from a common shaft comprising a shifting arm adapted to be swung about an axis and also movable in an axial direction a driving pinion carried by the shifting arm and means for actuating the driving pinion from the common shaft comprising transmitting gears mounted coaxially with the axis of the shifting arm and on said arm.

11. The combination with a plurality of devices to be actuated each provided with an internally toothed driving gear the axes of the driving gears being parallel and in the same plane, of means for actuating any one of said driving gears at will from a common shaft comprising a shifting arm adapted to be swung about an axis and also movable in an axial direction a driving pinion carried by the shifting arm and means for actuating the driving pinion from the common shaft comprising a sleeve mounted concentrically with the axis of the shifting arm and carrying a wide faced gear and transmitting gears carried by said arm.

12. The combination with a plurality of devices to be actuated each provided with a driving gear the axes of the driving gears being parallel, of means for actuating any one of said driving gears at will comprising an arm carried by a shifting shaft adapted to be oscillated about its axis and also movable in an axial direction, a driving pinion carried by said arm, means for actuating the driving pinion, a locating arm mounted on the shifting shaft and a fixed segment for cooperation with the locating arm.

13. The combination with a plurality of devices to be actuated each provided with a driving gear, the axes of the driving gears being parallel, of means for actuating any one of said driving gears at will comprising an arm carried by a shifting shaft adapted to be oscillated about its axis and also movable in an axial direction, a driving pinion carried by said arm, means for actuating the driving pinion, an operating arm mounted on the shifting shaft, a spring acting on the shifting shaft to move it axially in a direction to hold the driving pinion in engage-

ment with one or another of the driving gears of the devices to be actuated.

14. The combination with a plurality of devices to be actuated each provided with a driving gear, the axes of the driving gears being parallel, of means for actuating any one of said driving gears at will comprising an arm carried by a shifting shaft adapted to be swung about its axis and also movable in an axial direction, a driving pinion carried by said arm, means for actuating the driving pinion carried by said arm, means for actuating the driving pinion, a brake for each of the devices to be actuated and means operated by the movement of the shifting shaft for releasing the brake of one or another of the devices to be actuated.

15. The combination with a plurality of devices to be actuated each provided with a driving gear, the axes of the driving gears being parallel, of means for actuating any one of said driving gears at will comprising an arm carried by a shifting shaft adapted to be oscillated about its axis and also movable in an axial direction, a driving pinion carried by said arm, means for actuating the driving pinion, an operating arm mounted on the shifting shaft, a brake for each of the devices to be actuated, and means operated by the oscillating movement of the shaft for releasing the brake of one or another of the devices to be actuated.

16. The combination with a plurality of devices to be actuated each provided with a driving gear, the axes of the driving gears being parallel, of means for actuating any one of said driving gears at will comprising an arm carried by a shifting shaft adapted to be oscillated about its axis and also movable in an axial direction, a driving pinion carried by said arm, means for actuating the driving pinion, an operating arm mounted on the shifting shaft, a brake for each of the devices to be actuated, and means operated by the oscillating movement of the shaft for releasing the brake of one or another of the devices to be actuated comprising a brake shaft for each shaft and cam carried by the shifting shaft, each of the brake shafts having an operating arm extending into the path of movement of the cam.

This specification signed this 4th day of January, A. D. 1926.

CURTIS HUSSEY VEEDER.
